(57) **CLAIM**

The ornamental design for suture tabs, as shown and described.

DESCRIPTION

FIG. 1 is a perspective view of suture tabs showing the claimed design;

FIG. 2 is a top view thereof;

FIG. 3 is a bottom view thereof;

FIG. 4 is an enlarged right side view thereof;

FIG. 5 is an enlarged left side view thereof;

FIG. 6 is a front view thereof;

FIG. 7 is a rear view thereof;

FIG. 8 is a perspective view showing the suture tabs of FIGS. 1-7 in an alternative configuration;

FIG. 9 is a perspective view of suture tabs showing the claimed design;

FIG. 10 is a top view thereof;

FIG. 11 is a bottom view thereof;

FIG. 12 is an enlarged right side view thereof;

FIG. 13 is an enlarged left side view thereof;

FIG. 14 is a front view thereof;

FIG. 15 is a rear view thereof;

FIG. 16 is a perspective view showing the suture tabs of FIGS. 9-15 in an alternative configuration;

FIG. 17 is a perspective view showing the suture tabs of FIGS. 9-15 in an alternative configuration; and,

FIG. 18 is a perspective view showing the suture tabs of FIGS. 9-15 in an alternative configuration.

The broken line showing of the medical device is included for the purpose of illustrating environmental structure and forms no part of the claimed design.

The dot-dashed broken lines in the Figures show boundaries that form no part of the claimed design.

1 Claim, 14 Drawing Sheets
